Specification for Design.

Patented Sept. 26, 1916.

Application filed August 11, 1915. Serial No. 45,055. Term of patent 14 years.

To all whom it may concern:

Be it known that I, CHAUNCEY W. ABBOTT, a citizen of the United States, residing at Pittsburgh, in the county of Allegheny and State of Pennsylvania, have invented a new, original, and ornamental Design for Right-Hand-Twisted Elbow-Bases for Fittings for Electrical Conduits, of which the following is a specification, reference being had to the accompanying drawing, forming part thereof.

In the drawings, Figure 1 is an elevation illustrating a side view of the ceiling leg and a front view of the side wall leg, Fig. 2 is an elevation showing an end view of the ceiling

leg and a side view of the side wall leg, and Fig. 3 is a bottom plan view illustrating a bottom view of the ceiling leg and a bottom or end view of the side wall leg of a right hand twisted elbow base for fittings for electrical conduits, showing my new design.

I claim:

The ornamental design for a right hand twisted elbow base for fittings for electrical conduits, as shown.

CHAUNCEY W. ABBOTT.
